UNITED STATES PATENT OFFICE

2,562,027

ARRANGEMENT IN HIGH-TENSION CONNECTING SWITCHES

Haakon Forwald, Valhalla, Ludvika, Sweden, assignor to Allmanna Svenska Elektriska Aktiebolaget, Västerås, Sweden, a Swedish corporation

**Application January 17, 1948, Serial No. 2,926
In Sweden July 25, 1946**

Section 1, Public Law 690, August 8, 1946
Patent expires July 25, 1966

Section 1, Public Law 690, August 8, 1946
Enacted June 25, 1966

3 Claims (CL 200-48)

1

In electric disconnecting switches having a movable contact arm engaging a stationary contact, the motion of the arm is frequently prevented by, for example, an ice formation at the contact point, or when the contacts have been welded together due to an arc formation between them. To facilitate the motion of the contact arm when such ice formation or welding has occurred, disconnecting switches have been so designed that when the switch is opened there is a rotating component in the sliding motion between the contact surfaces. Due to this rotating component between the surfaces, the ice or weld is readily broken so that the opening motion may be readily performed. In a known form of disconnecting switches, this rotating component between the contact surfaces has been obtained by arranging the stationary contact to swing in the same plane as the contact arm around a pivot located at a distance from the contact point. In the known form, the stationary contact is actuated by a spring acting in the same direction as the force exerted on it by the frictional force from the contact arm when the switch is opened.

According to the present invention, the spring acting on the swinging stationary contact is so arranged that it normally forces the swinging contact against a lower stop, and further, the stationary contact consists of two parallel contact horns forming a vertical contact gap, the said horns being actuated by springs and being held in such a position in relation to each other that the distance between them is less than the breadth of the movable contact, and the horns are forced sidewise by the movable contact when it enters the contact gap.

On the accompanying drawing, Fig. 1 is a side view of the disconnecting switch, partly in section, and Fig. 2 is a cross-section through the movable contact of the switch, showing engagement thereof between the stationary contact horns.

On the drawing 1 designates the disconnecting switch arm, which is pivoted in a support 2 attached to the insulator 3. The swinging of the arm is effected by a device not shown on the drawing. The stationary contact 4 of the disconnecting switch consists of two horns 4, each consisting of a bar bent in an acute angle, one leg of each horn being secured to a block 5 movable on a pivot 6, while the other legs, which are parallel to each other, form a vertical contact gap. The pivot 6 is journaled in a cap 9 attached to the insulator 10. In the cap 9 there

2

is an opening 11 through which the contact horns 4 project, and by the spring 7 the contact horns are forced against the lower edge of the opening 11, the upper and lower extremities of said opening 11 serving as upper and lower stops for said horns. The current is delivered to the contact horns by the flexible connection 8.

When the contact attached to the arm 1 and the contact horns 4 become welded together, or when by other causes a sufficient friction exists between the contacts, the contact horns are raised when the arm 1 is moved upwards, until said horns reach the upper stops or end position determined by the edge 12, which position on the drawing is indicated by dotted lines in Fig. 1, and there will thus be a rotating component in the sliding motion between the contact surfaces when the switch is being opened.

This arrangement has the advantage that the contacts, when closing the switch, smoothly engage each other, due to the fact that the contact surfaces on the stationary contact horns are parallel, and when the contact arm enters between them, are moved sidewise only a very small distance, and due to the fact that the stationary contact device rests against the lower stop, there will be no rebound when the contact arm reaches the stationary contact with great velocity.

I claim as my invention:

- 30 1. An electric disconnecting switch comprising
a swinging contact arm, a movable contact se-
cured to the free end of said arm, two parallel
angularly bent contact horns having substan-
tially vertical and substantially horizontal leg
35 parts and serving as the stationary contact de-
vice for engagement with said movable contact,
said vertical leg parts forming a vertical con-
tact gap, a pivot arranged perpendicularly to
40 said horns and secured to said horizontal leg
parts, an insulator, journals for said pivot car-
ried by said insulator, upper and lower stops for
said horns, and a spring normally forcing said
horns against the lower stop, and having one
45 end connected to said insulator and the other
end connected to said horns.

2. An electric disconnecting switch, comprising a swinging contact arm, a pair of spaced members forming a normally stationary contact for engagement by the free end of said swinging contact arm, a pivot arranged perpendicularly to said spaced members and about which said members may turn when said contacts are being disengaged from each other, an insulator supporting said pivot, a stop device holding said members in their normal stationary position

and preventing yielding movement of the said members while being engaged by the swinging contact arm, a spring having one end stationary and the other end connected to the spaced members whereby said members are yieldingly held against said stop device, and a second stop device spaced from the first stop device and adapted to limit the movement of the said spaced members when the contacts are being disengaged from each other.

3. An electric disconnecting switch, according to claim 2, comprising a cap mounted on said insulator, journals in said cap for said pivot, and a slot in said cap, the extremities of said slot forming said stop devices for limiting the movement of said spaced contact members. 15
